METHOD OF HEATING

Oscar A. Ross, New York, N. Y.

Application November 15, 1927, Serial No. 233,482
Renewed September 13, 1934

20 Claims. (Cl. 237—12)

This invention relates to heating systems and more particularly to major heating systems employed in large buildings wherein extensive radiation is installed.

One object of this invention is to furnish a major heating system wherein a number of comparatively small buildings, or a number of sections of a large building may have steam, or other heating fluid, supplied thereto in sequential order, in this manner reducing the maximum supply of steam, generally termed "maximum demand" to a comparatively small amount, as compared to the "maximum demand" required if all the small buildings, or sections of the large building were supplied with the steam simultaneously.

Another object is to furnish a heating system wherein the aforesaid "sequential supply of steam" will be effected automatically as well as in accord with the outside temperature whereby the buildings, or sections, will be uniformly heated irrespective of variations of said outside temperature.

The invention in one of its embodiments is adapted for use in systems wherein condensate from a steam heating system is utilized for heating water supplied to hot water service pipes. The invention is also adaptable to heating systems for comparatively high buildings wherein the steam supplied to the system may be fed through risers at a comparatively high temperature to the point of distribution at an upper part of the building and thereafter reduced in pressure for supply to the radiators, in this manner permitting the use of comparatively small risers and reducing the condensation losses therein.

Other objects and advantages will appear as the description of the invention progresses and the novel features thereof will be pointed out in the appended claims.

The invention consists in such novel features, arrangements, combinations of parts and methods as are described in connection with the apparatus herein disclosed by way of example only. Novel features and combinations of the apparatus are disclosed and claimed in my copending divisional application Ser. No. 757,790, filed December 17, 1934. Other features, embodiments and combinations of the apparatus are disclosed and claimed in my copending application Ser. No. 515,761, filed February 14, 1931, comprising a continuation of my copending application Serial No. 56,283, filed September 14, 1925.

In describing the invention in detail, reference is had to the accompanying drawings, illustrating embodiments of the invention, and wherein like characters of reference designate corresponding parts throughout the several views, and in which:—

Figure 1 is a diagrammatic view of one form of heating system applied to a building; Fig. 2 is a

perspective view of a portion of the apparatus associated therewith; Fig. 3 is a sectional view of another part of said apparatus; Fig. 4 is a diagrammatic view of still another part of the apparatus; and Fig. 5 is a modified form of heating system shown diagrammatically.

Referring to Fig. 1, the building 1 is divided into three heated sections, 2, 3 and 4, each section having rooms a, b and c supplied with a radiator 5, having thermally controlled outlet valve 6, except room 2a which is preferably supplied with a hot water radiator 8 receiving hot water from boiler 30 through riser 8a and discharging said water through return 8b. The radiators 5 in section 2 are fed by riser 9, those of section 3 by riser 10 and those of section 4 by riser 11. The condensation from said radiators is returned from section 2 by return 12, from section 3, by return 13 and from section 4 by return 14, said risers and returns being connected to sequential distributing unit 15, each return having a trap 16 at the discharge end thereof. Each heated section 2, 3 and 4, forms a subsidiary heating system of the major system supplying heat to building 1.

Steam is assumed to be supplied from a public utility service main 17 through pipe 18 and thence to valve 19, meter 20, reducing valve 21, automatic cutout 22, and valve 23 to sequential distributing unit 15. The condensation from returns 12, 13 and 14 passes through traps 16, unit 15 and pipe 25 to pump 26 of known form for removing air, or vapors, thence through pipe 27, pressure check valve 28, heating coil 29 of boiler 30, pipe 31 having pressure check valve 32 and water meter 32a and thence to sewer 33.

The hot water heating boiler 30 receives water from service main 34 and distributes hot water to faucets 1 through risers 35.

Traps 16 have a common air and vapor withdrawal line 36 connected to the vacuum end of 40 the air discharge section of pump 26, the air being discharged to sewer 33 through pipe 37.

"Over-heat" thermostats 38 in sections 2, 3 and 4, are connected in multiple and arranged to energize automatic cut-off valve 22 for cutting off the steam supply upon any abnormal heating of said sections, a switch 39 manually controlling the flow of energy to wires 40, 41 and 42 of the circuit controlling said valve.

Referring to Figs. 2 and 4, showing sequential distributing unit 15 in more detail, motor 45 drives worm 46 engaging gear 47, mounted on shaft 48, also secured to which are distributor cams 2s, 3s and 4s and return cams 2r, 3r and 4r. The cam faces 49 of cams 2s, 3s and 4s are adapted to 55 depress valve stems 50 thereby opening supply valves 2sv, 3sv and 4sv. The cam faces 51 of cams 2r, 3r and 4r are adapted to depress valve stems 52 thereby opening return valves 2rv, 3rv and 4rv. Valve stems 52 each support a contact

spring 53 adapted to contact with a contact 54 and establish the "pump motor circuit" as follows: from positive energy to switch 59, wire 55a, motor 55, wire 56, pipe 25, a contact 53 in lowered position, contact 54, wire 57 and switch 59 to negative energy.

Referring to Fig. 4, gear wheel 47 preferably formed of insulating material, supports contact sector 62 substantially encircling the side thereof, the contact springs 63 and 64 bearing thereon, a sector space 65 being provided sufficient to permit the opening of the circuit to motor 45 when spring 64 enters such space.

Located in the outside atmosphere, preferably on top of building 1, is thermostatic device 70, more fully described in my said copending application Serial No. 56,283, filed September 14, 1925, and Ser. No. 515,761, filed February 14, 1931, the rheostat arm 71 lowering to cut out resistance 73 upon the lowering of the outside temperature and raising to add resistance upon the increase of said outside temperature. Said device controls the "thermostat control circuit" as follows: from positive energy to wire 75, arm 71, a contact 72, resistance 73, wire 76, night switch 77, wire 78, motor 74, to negative energy through wire 79, in this manner varying the speed of motor 74 proportionately to the variation of the outside temperature. Motor 74 drives worm 83, rotating contact drum 84, supporting contact 85, adapted to momentarily bridge contact springs 86 and 87.

Motor 45 rotates cams 2s, 3s, 4s, and 2r, 3r, and 4r through one heating cycle by establishment of the "heat supply circuit" as follows: from positive energy to wire 66, contact spring 63, contact 62, contact spring 64, wires 67, 68, motor 45 and wire 69 to negative energy. After gear 47 has completed a revolution in the direction shown by the arrow, contact spring 63 will enter space 65 thereby opening said circuit and motor 45 will stop. The relation of the space 65 and the various cams is such that motor 45 stops just after cam 4s has permitted valve 4rv to close and before valve 2sv is again opened. Likewise cam 4r permits the closing of valve 4rv and said motor stops before valve 2rv is again opened. After motor 45 has stopped, no flow of steam to, or flow of condensation from the system occurs and said motor remains stopped until contact 85 again bridges contact springs 86 and 87, whereupon the "frequency circuit" is established as follows: from positive energy to wire 90, contact spring 86, contact 85, contact spring 87, wires 91, 68, motor 45 and wire 69 to negative energy. As soon as motor 45 has again started contact 62 bridges contact springs 63 and 64 and energy is thereafter supplied from wire 66.

It is to be noted that each one of the contacts 72 has a dial indicating temperature of the outside atmosphere, and if desired the rod 70a and spring 70b may be removed and arm 71 operated manually from handle 70c.

It is also to be noted that when the atmosphere has reached 70° the arm 71 will move to the uppermost contact 72 to open the circuit to motor 74. If for any reason the arm should move onto said contact and motor 74 should stop with contact 85 bridging both springs 86 and 87, motor 45 would continue to operate for producing minimum heating. To avoid this unnecessary operation a contact spring 95 is arranged to engage contact 85 simultaneously with contact 86 whereby the "clearing circuit" is established as follows: from positive energy to wire 90, contact spring 86, con-

tact 85, contact spring 95, wires 96 and 78 to motor 74 and thence through wire 79 to negative energy. With this circuit established motor 74 operates until contact 85 has moved away from contact spring 86, in this manner also cutting off energy to motor 45 through contact spring 87.

Referring to Fig. 3, trap 16 comprises tank 100 provided with cap 101 supporting corrugated diaphragm 102, the interior of which communicates with passageway 103 and pipe 36, also check valve 104 constrained to seat by spring 105 permitting vacuum pipe 36 to withdraw air and vapors from the heating system through chamber 106 of tank 100, at the same time creating a partial vacuum within diaphragm 102, whereby float 107, and valve 108 secured thereto and to said diaphragm, will be raised to empty trap 16. Valve 108 is biased in both extreme upper and lower positions by weight 109 secured to one arm of bell crank 110, the other arm of which is pivoted to float 107. The chamber containing diaphragm 102 is open to atmosphere through opening 111.

The operation of the trap is as follows: during the "off" heating period of a section, as for example section 2, practically all the condensation collects in tank 100. As cam 2r acts to open valve 2rv and also starts pump 26, the vacuum produced by said pump causes a partial vacuum in the diaphragm 102, also raises valve 104 and creates a partial vacuum in the pipe lines and radiators of section 2, it being assumed that the radiators 5 have cooled sufficiently to open valves 6. As tank 100 will contain considerable condensation, the combined efforts of float 107 and diaphragm 102 will cause valve 108 to rise whereupon said condensation will flow to pump 26 and thence to heating coil 29 of hot water heater 30, said pump separating all air and vapors therefrom, passing the water only to said heater. After tank 100 has been emptied and pump 26 stopped, the air leakage back through said pump will nullify the vacuum in pipe 36 and diaphragm 102, thereby again permitting valve 108 to seat and seal the return line preparatory to the next heating cycle and resulting condensation produced thereby.

Referring to Figs. 1, 2, 3 and 4, the operation of the system disclosed thereby is as follows: assume the outside temperature surrounding building 1 to be approximately 40° under which condition the arm 71 will be in contact with contact 40° as shown, thereby establishing the "frequency circuit" whereby motor 74 rotates contact 85 to establish the "heat supply circuit" to motor 45 at a frequency whereby the resulting heat supply periods will be rendered at sufficiently close intervals to adequately heat building 1 with an exterior temperature of approximately 40°.

After contact 85 has established the "heat supply circuit" and before gear 47 has rotated to again open said circuit as heretofore described, contact 85 will have moved sufficiently to have opened said circuit between contact springs 86 and 87, and as space 65 of gear 47 passes under contact spring 64, motor 45 will stop in a manner to maintain all the supply valves 2r, 3r and 4r closed until contact 85 again bridges contact springs 86 and 87.

If the outside temperature reaches 70° or higher, and at which time no artificial heat is required in building 1, the arm 71 moves to the 70° contact whereupon the energy to motor 74 is cancelled by device 70, thereby also stopping the motor 45 indefinitely.

If the outside temperature falls to 10°, arm 71

moves to the 10° contact 72 whereupon motor 74 operates at maximum speed thereby producing a maximum number of heating cycles by increasing the frequency thereof.

5 During each heating cycle produced by establishing the "heat supply circuit", and as motor 45 starts, cam 2r acts to open valve 2rv and drain section 2 of all condensation, thereafter the steam from pipe 18 is supplied to the subsidiary heating system of section 2 by action of the raised portion 49 of cam 2s in opening valve 2sv, said valve being maintained in open position for a period of time sufficient to fill all the radiators in section 2 with steam as well as maintain pressure there-
10 in until the radiator structure has attained a temperature substantially equivalent to that of the steam, whereupon said valve is closed.

A comparatively small interval of time after valve 2sv has closed, the raised portion 49 of cam 2s acts to open valve 3sv whereupon steam is supplied to radiators 5 of section 3 and after the subsidiary system therein has been filled with steam, the cam portion 49 of cam 4s acts to open valve 4sv whereupon steam is supplied to the subsidiary system in section 4 and as said last named raised portion 49 acts to close valve 4sv, the space 65 will have passed under contact spring 64 and motor 45 will be stopped with the raised portion 49 of cam 2s in a position to again effect the opening of valve 2sv. From the foregoing it will be noted that the steam has been supplied to the sections 2, 3 and 4, in sequential order during each heating cycle.

Substantially simultaneously with the opening 35 of valve 2sv, as described, the raised portion 51 of cam 2r will have passed away from valve stem 52 of valve 2rv thereby closing said valve. As described, when valve stem 52 is lowered and contact spring 53 engages contact 54, the valve 40 2rv is opened and pump 26 is started thereby draining trap 16 of condensation as well as establishing a partial vacuum in the subsidiary system of section 2, and as supply valve 2sv opens, steam from supply pipe 18 will quickly fill said system, 45 the thermally controlled valves 6 preventing the steam from entering the return 12 until the condensation thereof is effected.

A predetermined interval of time before cam 3s acts to open supply valve 3sv, the cam 3r will 50 act to open return valve 3rv whereby trap 16 in return line 13 will be drained of its condensation and a partial vacuum will be established in the radiators 5 and risers 10 of section 3 prior to the opening of supply valve 3sv by cam 3s.

55 A similar sequence of operations will occur in draining condensation from and supplying steam to the subsidiary heating system of section 4 and thereafter motor 45 will stop until another heating cycle is initiated by establishing the 60 "heat supply circuit" by contact 85.

From the foregoing it will be noted that by sectionizing a building as 1, for heating purposes, and supplying steam to a subsidiary heating system in each section sequentially, a comparatively small "maximum demand" of the steam is required thereby reducing the yearly "maximum demand" charge usually made by the concern supplying said steam.

The number of subsidiary heating systems and 70 the radiation therefore is preferably proportioned whereby during the coldest weather, and upon the completion of a heating cycle, the drum 84 will have made a complete revolution and contact 85 will again establish the "heat supply 75 circuit", in this manner producing a substantially

continuous supply of heat to building 1, the supply calling for a comparatively low "maximum demand" from the source.

It is to be noted that the subsidiary heating systems of sections 2, 3 and 4, may be employed 5 to heat detached buildings, one of the buildings containing the distribution apparatus 15 and auxiliary devices therefor.

In certain buildings where a comparatively 10 small quantity of hot water is required, the surplus hot water from boiler 30 may be supplied to a hot water radiator 8 in room 2a, the cam 15 2s being adjusted to supply a proportionately lesser quantity of steam to the heating system in section 2.

Whereas pipe 36 connects the vacuum side of pump 26 to all the traps 16, the partial vacuum established in diaphragms 102 will not be sufficient to raise the valve 104 in other than the selected trap in which the condensation acting 20 on the float will effect the raising of said valve.

Traps 16 are preferably of a capacity whereby substantially all the condensation from their correlated section, as 2, 3 or 4 will return thereto before float 107 will rise with the assistance of 25 diaphragm 102. The variable capacity of tanks 100 is preferably secured by insertion of fixed bodies as 100a therein acting as liquid displacers.

If desired a rheostat 68a arranged to be varied 30 by arm 68b insulatively supported by arm 71 and arranged to be shunted by switch 68c may be placed in series with motor 45 whereby said motor is slowed down as the outside temperature is lowered, in this manner effecting comparatively longer supply periods of the steam to each section during each heating cycle, such longer supply periods, under certain conditions, being required to compensate for the more rapid cooling of the radiators during colder weather.

At night or at other non-working hours when 40 it is desired to maintain a lower temperature in the building, night switch 71 is opened, thus throwing resistance 80 into the circuit of motor 74. This results in this motor operating at a lower speed, thus increasing the time interval 45 between heating periods.

Whereas the raised cam faces 49 and 51 are shown as of a definite length, they may be made of variable length as shown in the Patent 1,178,170 to Marks, April 4, 1926.

The cam faces 49 of supply cams 2s, 3s and 50 4s are preferably formed whereby the valves 2sv, 3sv and 4sv opened thereby will remain open for a period sufficient to fill all the radiators as well as insuring that the radiator structure will assume 55 a temperature substantially that of the steam therein.

The cam faces 51 of return cams 2r, 3r and 4r are preferably formed whereby the valves 2rv, 3rv and 4rv are opened for a period of time sufficient to drain all the condensation from their correlated traps 16 and also permit the forming of a partial vacuum in the returns and radiators whereby rapid filling thereof occurs when the supply valves are opened.

Whereas the building 1 has been shown as sectioned in vertical planes, comparatively high office buildings, or similar structures are preferably sectioned in horizontal planes, the steam being supplied to unit 15 at a comparatively high 70 pressure and suitable reducing valves placed at the upper end of the risers for reducing the pressure of the steam as supplied to the radiators 5, this arrangement permitting the use of comparatively small capacity risers thereby reducing the 75

condensation therein as well as reducing the cost of installation.

Whereas one return pump as 26 has been shown for controlling all the flow of condensation, a similar pump may be employed for each section 5 2, 3 and 4, for independently controlling the flow of condensation therefrom and establishing the partial vacuum therein.

Whereas the steam supply has been shown as 10 a public utility service main, a suitable steam boiler may be employed therefor.

Referring to the modified form of heating system shown in Fig. 5, the thirty-six story building 200, having basement 201, is shown as sectioned in horizontal planes A to J, each section being assumed to contain four floors 1J, 2J, 3J and 4J, each floor having a heat radiating system 15 202 forming a portion of the subsidiary heating system supplied with low pressure steam from feeder line 210, said line receiving steam from high pressure riser 203 through reducing valve 204, each system being drained by a return 205.

In this major heating system, the subsidiary heating system of each section A to J is preferably supplied with independent condensation and vacuum pumps 26 arranged to establish a partial vacuum in each subsidiary system just prior to the supply of the steam thereto.

Comparatively high pressure steam from public 30 utility service main 17, or from high pressure boilers, is fed through distributing device 207 and through risers 203 to the reducing valves 204, thereby permitting the use of comparatively small risers and reducing condensation.

The reducing valves 204 form the origin of the 35 low pressure distribution to the subsidiary systems from whence the steam and condensation is "down-fed" through feeder line 210 and radiating system 202 to returns 205.

Owing to the larger volume of steam in the longer risers, as 203H and 203J, the distributor cams 49 of unit 207, are preferably formed to effect comparatively shorter time intervals of opening the supply valves as 2sv, than the similar 45 cams opening similar valves to the risers 203A and 203B, thereby equalizing the supply of steam by permitting the high pressure steam of the longer risers to expand into the subsidiary systems through the reducing valves 204.

Steam distributing unit 207, is similar to unit 50 15, being modified to include a larger number of supply and discharge valves, as 2sv and 2rv and correlated cams and circuit closers therefor.

A pipe 208 connecting each trap and correlated 55 pump 26 replaces the pipe 36 commonly connected to all the traps 16 of Fig. 1, and a pipe 209 commonly connected to all the air outlets of the pumps 26 conveys the air and vapors discharged thereby to the sewer 33.

While the invention has been described with 60 respect to certain particular preferred embodiments which give satisfactory results, it will be understood by those skilled in the art, after understanding the invention, that various changes and modifications may be made without departing from the spirit and scope of the invention, and it is intended therefore in the appended claims to cover all such changes and modifications.

I claim:

70 1. The method of supplying heat from a source to a plurality of subsidiary heating systems forming a major heating system arranged to heat a plurality of enclosed spaces which involves, establishing a flow of the heat from the source to each subsidiary system for one period of time alternate-

ly with cancelling the flow for another period of time, the flow periods being established to each subsidiary system at predetermined successive time intervals and the time interval of the non-flow periods being sufficiently long to permit completing the heat flow period to the last subsidiary system before again establishing the heat flow to the first subsidiary system.

2. The method of supplying heat in cycles from a source to a plurality of subsidiary heating systems forming a major heating system arranged to heat a plurality of enclosed spaces which involves, establishing timed flows of heat from the source to each subsidiary system successively during each heat cycle and varying the frequency of the cycles in response to the variations in temperature of atmosphere outside the spaces.

3. The method of supplying heat from a source to a plurality of subsidiary heating systems forming a major heating system arranged to heat a plurality of enclosed spaces which involves, successively establishing flows of heat from the source to each subsidiary system during one period of time alternately with cancelling the heat flows thereto during another period of time and varying the time interval of the heat flow periods in response to the variations in the temperature of atmosphere outside the spaces.

4. The method of supplying heat from a source to a plurality of subsidiary heating systems forming a major heating system arranged to heat a plurality of enclosed spaces which involves, successively establishing flows of heat from the source to each subsidiary system during one period of time alternately with cancelling the heat flows thereto during another period of time and varying the time interval of the non-flow periods in response to the variations in temperature of atmosphere outside the spaces.

5. The method of supplying heat in cycles from a source to a plurality of subsidiary heating systems forming a major heating system arranged to heat a plurality of enclosed spaces which involves, successively establishing timed flows of heat from the source to the subsidiary systems during each cycle and simultaneously varying the length of time of the timed flow periods and the frequency of the cycles in response to variations in temperature of atmosphere outside the spaces.

6. The method of supplying heat from a source to a plurality of subsidiary heating systems forming a major heating system arranged to heat a plurality of enclosed spaces which involves, successively establishing timed flows of heat from the source to the subsidiary systems alternately with cancelling the flow thereto, the cancellation of the flow period to one subsidiary system being effected before the establishment of a flow period to a succeeding subsidiary system.

7. The method of supplying steam in cycles from a source to a steam heating system for heating one or more enclosed spaces which involves, draining the condensation from the system and establishing a partial vacuum therein during one portion of the cycle, then establishing a flow of the steam from the source to fill the system during a succeeding portion of the cycle, and then cancelling the steam flow and permitting the system to heat the spaces during the remaining portion of the cycle.

8. The method of supplying steam from a source to a steam heating system for heating one or more enclosed spaces which involves, draining the condensation from the system and establishing a partial vacuum therein during one period

of the cycle, then establishing a flow of steam from the source to fill the system during a succeeding portion of the cycle, and then cancelling the steam flow and permitting the system to heat the spaces during the remaining portion of the cycle, the time interval of the last named period of the cycle being varied in response to variations in the temperature of atmosphere outside the spaces.

9. The method of supplying heat in periodic cycles from a source to a plurality of subsidiary heating systems forming a major heating system arranged to heat a plurality of enclosed spaces which involves, establishing independently timed flows of heat from the source to each subsidiary system in a predetermined sequence during the initial portion of the cycle and cancelling the heat flow thereto during the final portion of the cycle, the time interval of the final portion of the cycle being varied in response to the variations in the temperature of atmosphere outside the spaces.

10. The method of supplying heat in periodic cycles from a source to a plurality of subsidiary heating systems forming a major heating system arranged to heat a plurality of enclosed spaces which involves, establishing independently timed flows of heat from the source to each subsidiary system in a predetermined sequence during the initial portion of the cycle and cancelling the heat flow thereto during the final portion of the cycle, the time interval of the independently timed flow periods being varied in response to variations in temperature of atmosphere outside the spaces.

11. The method of supplying steam from a source to a plurality of subsidiary heating systems forming a major heating system which involves, periodically establishing flow of the steam from the source to the major system in inverse proportion to variations in temperature of the outside atmosphere, and during each periodic flow supplying the steam thereof successively to the subsidiary systems.

12. The method of heating a plurality of enclosed spaces heated by a plurality of subsidiary heating systems forming a major heating system which involves, establishing flow of heat from a source to the major heating system in inverse proportion to variation in temperature of the atmosphere outside the spaces and during each periodic flow apportioning the heat thereof successively to the subsidiary systems.

13. The method of supplying steam from a source to a plurality of subsidiary heating systems forming a major heating system which involves, establishing flow of steam from the source to the major system at predetermined and variable periods alternately with cancelling the flow for other predetermined and variable periods, and during each periodic flow apportioning the steam thereof successively to the subsidiary systems.

14. The method of heat regulation of buildings which are provided with valves for controlling individual heat supply risers, which consists in automatically alternating the supply of heat to adjacent risers according to a predetermined time interval.

15. The method of heat regulation of buildings which are provided with valves for controlling individual heat supply risers, which consists in automatically alternating the supply of heat to

adjacent risers according to a predetermined time interval and continuously testing outdoor temperatures and automatically varying said time intervals according to said outdoor temperature variations.

16. The method of heat regulation of buildings which are provided with valves for controlling individual heat supply risers, which consists in automatically alternating the supply of heat to adjacent risers according to a predetermined time interval during work hours and then automatically alternating the supply of heat to said risers at a different time interval during non-working hours.

17. The method of regulating the supply of heat to relatively large buildings having individual valve control for each heat supply riser and divided into a plurality of heating sections, with the controls for each section in closely adjacent relation, which consists in automatically alternating the supply of heat to adjacent risers according to a predetermined time schedule, and providing for control of groups from a central point.

18. The method of regulating the supply of heat to relatively large buildings having individual valve control for each heat supply riser and divided into a plurality of heating sections, with the controls for each section in closely adjacent relation, which consists in automatically alternating the supply of heat to adjacent risers according to a predetermined time schedule, and providing for control of groups from a central point, and then automatically varying said time schedule according to outdoor temperatures.

19. The method of controlling the supply of steam from a common source to radiators located in a plurality of zones of a building or structures to be normally heated to substantially a uniform temperature while affected by variations in outdoor temperature, which comprises providing supplies of steam from the source to the radiators of each zone during spaced time intervals, the intervals of supply for one zone being interspersed with the intervals of supply for another zone, and automatically controlling thermostatically in response to outdoor temperature variations, the relative lengths of said supply intervals as compared with the intervening periods, to regulate the rate of steam supply inversely in accordance with outdoor temperature changes, said intervals of supply normally being of sufficient frequency to enable substantially continuous maintenance of predetermined temperatures in the structures heated.

20. The method of controlling the supply of steam from a common source to radiators located in a plurality of zones of a building or structures to be normally heated to substantially a uniform temperature while affected by variations in outdoor temperature, which comprises providing supplies of steam from the source to the radiators of each zone during spaced time intervals, the intervals of supply for one zone being interspersed with the intervals of supply for another zone, and varying the rate of such supply of steam to each zone inversely in accordance with substantial changes of outdoor temperature, said intervals of supply normally being of sufficient frequency to enable substantially continuous maintenance of predetermined temperatures in the structures heated.
